UNITED STATES PATENT OFFICE

HAROLD E. HOUSEMAN, OF EDGE MOOR, DELAWARE, ASSIGNOR TO STANDARD-TRUMP BROS. MACHINE COMPANY, OF WILMINGTON, DELAWARE, A CORPORATION OF DELAWARE.

PLATED KNITTED FABRIC

Original application filed March 15, 1928, Serial No. 261,733. Divided and this application filed February 12, 1929. Serial No. 339,326.

It is known that to knit plated fabric, that is, fabric which is formed of a backing or body yarn and a facing or plating yarn, by feeding these two yarns under different tension simultaneously to the needles; the plating yarn appearing on the face of the fabric, while the body yarn is concealed. It is also known to produce striped and figured effects and designs by causing certain of the needles to engage only the body yarn and escape engagement with the plating yarn, so that only the body yarn will be knitted by these needles to form loops, while the plating yarn will float across the fabric. It is also known to produce striped and figured effects and designs by causing the two yarns knit by certain of the needles to be reversed in position so that the body yarn will appear on the face of the fabric knit by these needles, while the plating yarn is concealed.

The two methods of producing these striped and figured effects in plated knitted fabric may be designated respectively as the floating thread method and the reverse plating method. Examples of the first method are found in patents issued to Harold E. Houseman June 7, 1927, Nos. 1,631,816 and 1,631,817. An example of the second method is disclosed and claimed in an application filed by Wilbur L. Houseman July 29, 1927, Serial No. 209,383.

In the said patents issued to H. E. Houseman, these needles (which may be called regular needles) that are not to produce the striping effect are drawn down at such point in the rotation of the needle cylinder that the needles will engage both threads and knit them together. Those needles (which may be called special needles) that are to produce the striping effect are drawn down at such point in advance of the point at which the regular needles are drawn down that they will engage one of the threads (e. g., the body thread) and not the other (e. g., the plating thread), thus knitting only the former.

In the said application filed by W. L. Houseman, pressers, rotatable with the needles, are actuated by non-rotatable cams to bend selected needles inward out of their normal knitting plane, thereby reversing the

normal positions of the threads in those needles, so that the body or backing yarn will, in the wales formed by such needles, appear on the face of the fabric, producing a striped effect. This mechanism is hereinafter particularly described. Automatic pattern-controlled mechanism for actuating such cams in such manner as to actuate needles at will and produce any desired design is known in the art.

Both of these processes are limited to the production, in plated fabric, of two-color effects, since the use of only two threads is contemplated. The object of the present invention is to produce plated knitted fabrics having three-color effects, such as striped fabrics; or designs of various configurations that may be produced by knitting stripes of any desired length along any wales of the fabric that may be selected, each of said stripes being formed by causing any one of the three threads to appear on the surface while the other threads are concealed thereby or are caused to escape the needles and float across the fabric.

A circular plated knitted fabric comprising three threads each of which extends around the fabric along successive courses thereof and each of which appears on the face of the fabric in different parts of the fabric is not broadly my invention. A fabric of this character is disclosed in the application filed by Charles B. Gallagher March 15, 1928, Serial No. 261,739, Patent No. 1,744,219, and other fabrics of this character are disclosed in applications filed by me March 15, 1928, Serial No. 261,734, Patent No. 1,750,007, and April 20, 1928, Serial No. 271,428 Patent No. 1,746,433. The fabric claimed herein is a specific improvement on the fabric disclosed in said Gallagher application. In order to enable those skilled in the art to produce my improved fabric, I have herein fully described a practicable process and practicable mechanism by means of which such fabric may be produced. Such process, which is not limited in its use to the production of the fabric herein claimed, is also set forth and claimed in an application filed by me March 15, 1928, Serial No. 261,733, of

which this application is a division. The fabric herein claimed is, of course, not limited to the process herein described for producing it.

5 In so carrying out said process as to produce the fabric herein particularly described and claimed, three threads are fed simultaneously to a circle of knitting needles. A relatively strong tension is imposed on one of the 10 threads, say the plating thread, so that normally it will appear on the face of the fabric. A medium tension is imposed on another thread, which may be called the middle thread, so that normally it will appear in the 15 middle of the fabric directly under, and concealed by, the plating thread. No tension, or a relatively slight tension, is imposed on the third, or backing, thread, so that normally it will appear on the back of the fabric 20 and be concealed by the other two threads.

This triple thread fabric, in and of itself, exhibits substantial advantages over the two-yarn plated fabric that is well known in the art, and regardless of any difference in 25 the color of the three threads. Thus, it is possible to knit a fabric having a facing of silk and a backing of cotton in which the silk comprises only one-third, instead of one-half, of the fabric.

25 In order to produce the desired striped effects, I select and combine with each other and with the three threads subjected to the differential tension described, the methods of operation set forth in the different patents aforesaid so as to provide a novel method adapted to secure the results sought. To practice such novel method, it is preferred to use certain mechanism hereinafter described.

In the drawings:

30 Fig. 1 is a diagram of a series of needles, the yarn feed and the needle actuating cam; constituting part of the mechanism which it is preferred to use.

35 Figs. 2, 3 and 4 are diagrams of needles and adjacent sinkers, showing the relative positions of the three threads as they are knit into, or floated in, the fabric to bring the different threads respectively onto the face.

40 Fig. 5 is a diagram of a part of Fig. 1, enlarged, showing how certain needles engage all the threads and other needles only one thread preparatory to forming the stitches.

45 Fig. 6 is an elevational view, mainly in section, of a part of the needle cylinder and of the means for selectively pressing back needles to produce, in the hooks thereof, the arrangement of threads shown in Fig. 3.

50 Fig. 7 is a detail view of the upper ends 50 of two needles, one in normal position and the other bent back.

Fig. 8 is a detail view of one of the needle presser actuating jacks of Fig. 6.

55 Figs. 9, 10, 11 and 12 are diagrams showing the stitch cam and needles actuated thereby;

Fig. 9 also showing the means for moving the stitch cam into and out of operative position to actuate certain needles to cause them to escape engagement with certain threads as shown in Fig. 4.

Fig. 13 is a face view of a typical three-color design that may be produced in a plated fabric embodying my invention.

Fig. 14 is a diagram, enlarged, of a small section of a plated fabric embodying my invention, with the three different threads on the face in different parts thereof.

Specifically, and in order to illustrate one of different ways of producing my improved product, let it be assumed that, in the knitting of normal plated fabric, three differently colored threads are fed simultaneously toward a common point in the circle of needles. One possible arrangement of the threads is shown in Fig. 5. The backing yarn *b* is under a relatively light tension or substantially no tension. The plating or facing yarn *p* may be under strong tension. The middle yarn *m* may be under a medium tension. The needles *t*, *t*, follow the regular path, so that their hooks engage all the threads. In accordance with the principles governing the operation of plating, the plating thread *p*, being under higher tension, crosses over the middle thread *m*, and the three threads are 55 knit into the fabric in the order *p*, *m*, *b*, as shown in Fig. 2, so that the plating thread appears on the face of the fabric and the backing thread appears on the back of the fabric.

In order to make the backing thread appear on the face of the fabric the hook ends of the needles are pushed back, as shown in Fig. 3 (see also Fig. 7), causing the threads to roll around and reverse the relative order in which they are fed to the needles, so that the threads knit into the fabric in the order *b*, *p*, *m*, as shown in Fig. 3, so that the backing thread appears on the face of the fabric and the middle yarn on the back of the fabric.

In order to make the middle thread *m* appear on the face of the fabric, the needles are caused to move down prematurely (see the needle *u* in Fig. 5), so that they engage only the middle thread *m*. Therefore, only this thread is knit into the fabric, the other two threads floating across the fabric, as shown in Fig. 4.

It will be understood that in order to make the body of the stocking in one color with stripes of two contrasting colors, it is only necessary (in carrying out the process on a circular knitting machine in the illustrative way described) to operate certain (regular) 120 needles in the normal way, to set back out of the normal knitting plane other needles but operate them also in the regular way, and to operate a third set of needles prematurely 125 so as to cause them to move down prematurely 130

ly and engage only one of the threads (in the example given, the middle thread).

In order to produce three-color figured effects, it is necessary (in carrying out the process on a circular knitting machine in the described illustrative way) to provide means for selectively bending back selected needles for a predetermined number of courses and to prematurely move down into knitting position selected needles for a predetermined number of courses.

In order to selectively bend back needles it is preferred to utilize the mechanism disclosed and claimed in the said Wilbur L.

Houseman application, Serial No. 209,393, shown herein in Figs. 6, 7 and 8.

Vertically slidable in slots of the revolving needle cylinder *a* are the needles *t* and *u*, which are movable up and down in a normal knitting wave by cams operating in the usual way. Fastened to the needle cylinder is the sinker dial *c*, which carries the sinkers or web holders *i*, which cooperate with the needles in the usual manner to form the stitches.

Below the sinker dial *c* is a slotted jack dial *d*, which is attached to the sinker dial. Pressers *e* are placed in the needle cylinder slots after the needles have been inserted and are held in place by the two spring bands *k*. These pressers are so shaped that they bear against the needles at the extreme upper ends of the pressers and also at points opposite the spring bands *k*. The needle cylinder slots are of greater than normal depth at their upper ends, forming shoulders *q*. The needles are unsupported above these shoulders, which act as fulcrums when needles are pushed back by the upper ends of pressers *e*. The jack dial *d* has slots corresponding in number with the slots in the needle cylinder. At intervals and in groups in accordance with a pattern which is to be formed in the knitted fabric, jacks *f* are inserted in the dial slots. These jacks are held lightly in contact with their corresponding needle pressers *e* by a spring band *n*.

A threaded clamp ring *h* holds the jacks in their proper vertical position. The jacks are formed with slots on their rear ends so that sections may be broken out in different places leaving butts *o*, which may be in any one of eight different vertical positions. If desired, there may be two or more butts on a jack. The one illustrated in Fig. 8 has butts in all eight positions, whereas the one shown in Fig. 6 has a butt in only the second highest position.

The eight cams *g* for operating butts *o* in the eight different positions do not revolve and may be moved into or out of the path of the respective butts *o* of jacks *f*, each of the eight different cams being in alignment with one of the corresponding eight butt locations on the jacks.

When one or more of the eight cams *g* are

moved and held in the path of the jacks *f* having butts *o* corresponding to the vertical positions of such cams, these jacks will be pushed inward and will in turn rock the corresponding pushers *e*, thereby springing the corresponding needles at the fulcrum point *q*, causing their hooked ends to be bent back out of line with the adjacent unpushed needles in the normal knitting plane.

In order to prematurely move down into knitting position selected needles, it is preferred to use the mechanism disclosed in my Patents Nos. 1,631,816 and 1,631,817, a part of which is shown herein Figs. 9-12.

In Fig. 1 an arcuate group of needles *t*, vertically slidable in the needle cylinder, is shown in operative relation with the three threads *b*, *p* and *m*, which are fed from a yarn carrier *z* (Fig. 5) that is projected into the throat of the latch ring *s*. In the same figure is shown a group of cams, which are constructed in the usual way except that the stitch cam *w* is specially constructed and is operable radially by being carried on a radially movable slide *y* (see Fig. 9). The stitch cam is widened, at its upper forward corner, to provide a part *x* overhanging the inner side of the cam. The part *x*, which is in effect a supplemental cam, has a cam face aligning with the regular cam face of cam *w*.

The needles *t* (see Figs. 9 and 11), which may be designated regular needles, are of ordinary construction with the usual butts. The needles *u* (see Figs. 10 and 12), which may be designated special needles, are of the same construction except that they are provided with shoulders *v*.

If the stitch cam is moved out, as shown in Figs. 11 and 12, the cam *x* is not in line of travel of the shoulders *v*, and all the needles are operated, in the regular way, by the engagement of their butts with the cam *x*, and all the needles are operated in the same point in the circumference of the needle cylinder, and all the needles engage all three threads *b*, *p* and *m*. When, however, the stitch cam is moved in, as shown in Figs. 9 and 10, the supplemental cam *x* is in line of travel of the shoulders *v* of the special needles, and the special needles will move down at a point in the circumference of the needle cylinder in advance of the point at which the regular needles are moved down and at such point as to engage only the thread *m* and escape engagement with the threads *p* and *b*, thereby causing the latter threads to float back of the knitted-in thread *m*, as shown in Fig. 14.

In the said Patents 1,631,816 and 1,631,817, the needles in the front half, and the needles in the rear half, of the machine are shown as differently constructed and the stitch cam is shown as movable into several different radial positions, in order that the special needles may be operated as regular needles in knitting the heel and toe. Pattern-controlled

mechanism adapted to actuate the stitch cam *w*, *x*, and thereby selectively prematurely depress needles for any desired number of courses is known. Pattern-controlled mechanism adapted to selectively actuate the cams *g* and thereby selectively bend back the hook ends of needles for any desired number of courses is known. By means of such known mechanism, or by means of other mechanism 10 that may be devised, to control the operation of the mechanism herein described and shown, the process may be so practiced as to produce fabric, embodying my invention, exhibiting an infinite variety of three-color figures and designs.

In said Patent No. 1,631,817 a preferred, but more complicated, type of stitch cam is disclosed.

A section of fabric knit in accordance with the herein described process and embodying my invention is shown in Fig. 14, the drawing being made with the stitches far looser and far more open than in the actual fabric in order to more clearly illustrate its structure. 25 In the first two and the last two wales all three threads are knitted into the fabric, the plating yarn *p* appearing on the face. In the third and fourth wales, all three threads are knitted into the fabric, the backing yarn *b* appearing on the face. In the fifth and sixth wales, only the middle yarn *m* is knitted into the fabric, the other two threads floating across from the fourth wale to the seventh wale.

35 Having now fully described my invention, what I claim and desire to protect by Letters Patent is:

1. A plated knitted fabric including at least three threads all extending continuously along successive courses of the fabric and comprising normally plated wales of stitched loops in which one thread appears on the face, another on the back, and another in the middle, of the fabric, and other wales 45 whose stitched loops are formed by the third mentioned thread while the remaining threads float.

2. A plated knitted fabric including at least three threads all extending continuously along successive courses of the fabric and comprising normally plated wales of stitched loops in which one thread appears on the face, another on the back, and another in the middle, of the fabric, other wales of 55 stitched loops in which all three threads appear in a different order, and still other wales whose stitched loops are formed by one of the two last named threads while the remaining threads float.

3. A plated knitted fabric including at least three threads all extending continuously along successive courses of the fabric and comprising normally plated wales of stitched loops in which one thread appears 65 on the face, another on the back, and an-

other in the middle, of the fabric, other wales of stitched loops in which all three threads appear in a different order, and still other wales whose stitched loops are formed by the third mentioned thread while the remaining 70 threads float.

4. A plated knitted fabric including at least three threads all extending continuously along successive courses of the fabric and comprising normally plated wales of 75 stitched loops in which one thread appears on the face, another on the back, and another in the middle, of the fabric, and wales of stitched loops in which the second named thread appears on the face, the third named 80 thread on the back, and the first named thread in the middle, of the fabric, and still other wales whose stitched loops are formed by the third named thread while the remaining threads float.

5. A plated knitted fabric including at least three threads all extending continuously along successive courses of the fabric and comprising stitched loops in which one of 90 said threads appears on the face of the fabric in some parts of the fabric, another of said threads appears on the face of the fabric in other parts of the fabric and the remaining thread appears on the face of the fabric in still other parts of the fabric; all three 95 threads forming stitched loops in plating relation in different parts of the fabric but arranged in a different order from face to back in different parts of the fabric; two of said threads floating in other parts of the 100 fabric.

6. A plated knitted fabric including at least three threads all extending continuously along successive courses of the fabric and comprising stitched loops in which one 105 of said threads appears on the face of the fabric in some parts of the fabric, another of said threads appears on the face of the fabric in other parts of the fabric and the remaining thread appears on the face of the 110 fabric in still other parts of the fabric; a plurality of said threads forming stitched loops in plating relation, but arranged in a different order, in different parts of the fabric; two of said threads floating in other 115 parts of the fabric.

7. A knitted fabric including at least three threads, said fabric having a portion in which all three threads are knit into loops with one of said threads overlying the second 120 and third of said threads and with the second thread overlying the third, and another portion in which only the second thread is knit into loops while the other threads float.

8. A knitted fabric including at least three threads, said fabric having a portion in which all three threads are knit into loops with one of said threads overlying the second 125 and third of said threads and with the second thread overlying the third, and another portion 130

tion in which only the third thread is knit into loops while the other threads float.

9. A knitted fabric including at least three threads all extending continuously along successive courses of the fabric, said fabric having a portion in which all three threads are knit into loops with one of said threads overlying the second and third of said threads and with the second thread overlying the third, and another portion in which only the second thread is knit into loops while the other threads float.

10. A knitted fabric including at least three threads all extending continuously along successive courses of the fabric, said fabric having a portion in which all three threads are knit into loops with one of said threads overlying the second and third of said threads and with the second thread overlying the third, and another portion in which only the third thread is knit into loops while the other threads float.

11. A knitted fabric including at least three threads, said fabric having a portion in which all three threads are knit into loops with one of said threads overlying the second and third of said threads and with the second thread overlying the third, another portion in which all three threads are knit into loops with the third thread overlying the first and second of said threads and with the first thread overlying the second, and another portion in which only the second thread is knit into loops while the other threads float.

12. A knitted fabric including at least three threads all extending continuously along successive courses of the fabric, said fabric having a portion in which all three threads are knit into loops with one of said threads overlying the second and third of said threads and with the second thread overlying the third, another portion in which all three threads are knit into loops with the third thread overlying the first and second of said threads and with the first thread overlying the second, and another portion in which only the second thread is knit into loops while the other threads float.

13. A knitted fabric including at least three threads all extending continuously along successive courses of the fabric, said fabric having a portion in which all three threads are knit into loops with one of said threads overlying the second and third of said threads and with the second thread overlying the third, and another portion in which only one of the threads is knit into loops while the other threads float.

14. In testimony of which invention, I have hereunto set my hand, at Philadelphia, Penna., on this 7th day of February, 1929.

HAROLD E. HOUSEMAN.
